(57) **CLAIM**

We claim the ornamental design for a lamp control module, as shown and described.

DESCRIPTION

FIG. 1 is a front perspective view of a lamp control module according to a first embodiment of our new design.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is a rear perspective view of a lamp control module according to a second embodiment of our new design.

FIG. 10 is a front view thereof; and,

FIG. 11 is a bottom view thereof, the front perspective, rear, left side, right side, and top views, respectively, of the second embodiment being identical to the front perspective, rear, left side, right side, and top views of the first embodiment.
